ATTORNEY.

UNITED STATES PATENT OFFICE

ALFRED C. McCLOSKEY, OF PHILADELPHIA, PENNSYLVANIA

SAFETY BOX FOR MATCHES

Application filed June 20, 1928. Serial No. 286,822.

The object of this invention is to devise a novel construction of a safety box for matches which is adapted to receive the burnt matches.

In the usual form of match boxes in which the matches are ignited by striking them against friction material carried by the cover of the box, no provision is made for receiving and storing the burnt matches. The result is that a person who has ignited a match, carelessly throws it away without making sure that the match has been extinguished. Many fires have been caused by this carelessness and a large amount of property has been destroyed.

15 The primary object of this invention therefore, is to devise a novel safety box for matches wherein after a match has been lighted it can be moved into a storage space in the box, and if a match has not been fully 20 extinguished the act of moving it into the storage compartment will cause the match to be extinguished.

With the above and other objects in view which will hereinafter more clearly appear, 25 my invention comprehends a novel safety box for matches.

It further comprehends a novel match box provided with a movable partition in the match receiving compartment of the box and 30 with an aperture through which a burnt match can be inserted into the storage compartment for burnt matches.

It further comprehends a novel construction of a match box having a movable partition which contributes to form a compartment for the unburnt matches and a compartment for the burnt matches, the match box being provided with an opening through 35 which burnt matches can be introduced into the compartment provided therefor, and, at the same time, the partition will be moved as necessary for the reception of the burnt matches.

Other novel features of construction and 40 advantage will hereinafter more clearly appear in the detailed description and the appended claims.

For the purpose of illustrating the invention, I have shown in the accompanying drawings typical embodiments of it, which, in

practice, will give satisfactory and reliable results. It is, however, to be understood that the various instrumentalities of which my invention consist can be variously arranged and organized and my invention is not limited to the exact arrangement and organization of these instrumentalities as herein shown and described.

55 Figure 1 is a section on line 1—1 of Figure 2 of a safety match box embodying my invention.

Figure 2 is an end view of the construction seen in Figure 1.

Figure 3 is a section on line 3—3 of Figure 1.

60 Figure 4 is a transverse section of another embodiment of my invention in which the movable partition instead of being flat as in Figures 1, 2 and 3, is centrally deflected.

Figure 5 is an end view of another embodiment of my invention.

65 Figure 6 is a transverse section of the embodiment seen in Figure 5, showing more particularly the movable partition.

Figure 7 is a transverse section of another embodiment of my invention similar to that seen in Figure 6 except that the movable partition has its central portion bulged or laterally deflected.

70 Similar numerals of reference indicate corresponding parts.

Referring to the drawings:—

The match box, as illustrated, has a conventional rectangular open ended cover 1 into which the box 2 is slidable. The box 2 75 has its top open in the usual manner, and provides a match receiving compartment 3.

80 4 designates a movable partition of any desired material, for example wood or cardboard. This, as shown in Figures 1, 2 and 3, consists of a flat sheet of material, and contributes to form a compartment 5 for the reception of the used or burnt matches.

85 The matches are introduced into the compartment 5 through an opening 6 in the end of the box 2. If the box 2 is of cardboard a burr is formed inside of the box as shown at 7 in Figure 1, which will retain the partition 4 a sufficient height above the bottom 90 of the box to permit the introduction through 100

the opening 6 of the used matches. In case a burr is not formed at the inner end of the opening 6, a partition such as 8 in Figure 4, may be employed, in which the partition has a bent or bulged portion 9.

It is also within the scope of this invention to employ a vertical partition as seen in Figures 5 and 6, in which case the opening 11 is preferably located near one side edge of an end of the box. This partition may be flat as in Figures 5 and 6, or it may be deformed as at 12 in Figure 7.

As the box and cover are of conventional construction except as to the partition and opening to receive the used matches, I have identified corresponding parts by the same reference characters.

In all of the embodiments of my invention herein shown the box is provided with an opening through which the burnt matches are introduced into a compartment formed between the partition and a wall of the box. As such compartment is filled the partition advances until all of the unused matches have been used.

If a match has not been extinguished, the act of inserting it through the opening leading to the compartment for the used matches will cause such match to be extinguished.

It will be apparent that the dimensions and contour of the opening through which the matches are introduced into the compartment for used matches may vary widely in practice.

It will be seen that I provide in a large retainer spaces for the used and unused matches and as the space for the unused matches decreases by the removal of matches therefrom, the space for used matches correspondingly increases as such used matches are returned to the match retainer.

It will now be apparent that I have devised a new and useful safety box for matches which embodies the features of advantage enumerated as desirable in the statement of the invention and the above description, and while I have, in the present instance, shown and described preferred embodiments thereof of which will give in practice satisfactory and reliable results, it is to be understood that these embodiments are susceptible of modification in various particulars without departing from the spirit or scope of the invention or sacrificing any of its advantages.

Having thus described my invention what I claim as new and desire to secure by Letters Patent, is:—

1. A match box, comprising a box and a cover into which it is slideable, and a movable partition within the box at all times spaced from the juxtaposed wall of the box contributing to form a compartment for the unused matches and a compartment for the used matches, and said box having an opening in the end of the box through which used

matches can be introduced into the compartment therefor.

2. A match box, comprising a box having an open top and a cover into which said box is slideable, and a movable partition within said box, at all times spaced from the juxtaposed wall of the box, said cover having at one end an opening through which used matches can be introduced into the box beneath said partition.

3. A match box, comprising a box having an open top and a cover into which said box is movable, and a partition movably mounted within said box, said box having an opening in its end through which used matches can be introduced beneath said partition, and said box having means to space the partition in proximity to said opening above the bottom of the box.

4. A match box, comprising a box and a cover into which the box is movable, and a partition within the box and deformed to space it from a wall of the box, and said box having an opening in its end to permit the introduction of used matches between said partition and a juxtaposed wall of the box.
